Atty.

UNITED STATES PATENT OFFICE.

GEORGE W. DOVER, OF CRANSTON, RHODE ISLAND.

SCARF-PIN.

SPECIFICATION forming part of Letters Patent No. 746,049, dated December 8, 1903.

Application filed September 29, 1903. Serial No. 175,064. (No model.)

To all whom it may concern:

Be it known that I, GEORGE W. DOVER, a citizen of the United States, residing at Cranston, in the county of Providence and State of Rhode Island, have invented certain new and useful Improvements in Scarf-Pins, of which the following is a specification, reference being had therein to the accompanying drawings.

10 My invention relates to scarf-pins, and has for its object, in addition to the ends commonly sought by such devices, a method of uniting the pin-stem with the head of the scarf-pin without the use of solder. By the 15 methods heretofore employed the heating of the metals incident to the soldering operation has tended to weaken the scarf-pin at that point whereon the greatest strain is naturally brought.

20 The attainment of the ends above indicated is secured by the invention hereinafter described, and illustrated in the accompanying drawings, wherein—

Figure 1 is the side elevation of a blank 25 from which the pin-stem is to be ultimately formed; Figs. 2 and 3, similar elevations of the same in various stages of mechanical development; Fig. 4, a side view of my completed scarf-pin; Fig. 5, a vertical section of 30 the same upon line $\alpha\alpha$ of Fig. 6, showing parts of the pin and spur broken away; and Fig. 6, a transverse section of the same on line yy of Fig. 5.

Like reference-letters indicate like parts 35 throughout the views.

My new device is constructed as follows: A cylindrical blank A has formed at one side of its center a loop c, leaving a section of the blank b upon one side of the loop and a longer 40 section a upon the other side. The loop portion of the blank thus treated is next flattened, as shown in Fig. 2, in rectangular dies, which leaves the lower extremity c' of the flattened portion a smooth rectangular surface. The flattened portion is next pierced 45 with an opening d, which operation completes the pin-stem.

Upon the back of the scarf-pin head B rise two ears e, provided with transverse perforations f to receive a dowel-pin g, which traverses these openings and the opening d of the pin-stem. It will be observed that, as illustrated, the opening d in the pin-stem is

of somewhat greater diameter than the perforations f of the lugs. This formation admits of a more secure frictional engagement of the united parts than if the openings were all of equal diameter, yet it will be understood that this matter of detail is not vital, as an operative union may be effected by the employment of openings of equal diameter.

As shown above, at any convenient stage of the formation of the pin-stem the shorter section b may be pointed to form the usual spur, and the portion a may be pointed to 65 form the pin portion.

It will be noted from the above description that the use of solder has been entirely dispensed with and that a perfectly firm and unyielding union is effected by means of the 70 pressure of the flat face c' of the lug c upon the rear face of the head B.

Having described my invention, what I claim is—

1. In a scarf-pin, the combination with the 75 head of ears upon the head, a stem, a lug upon the stem provided with a flat extremity and resting upon the back of the head intermediate the ears, and means for uniting the lug and ears.

2. In a scarf-pin, the combination with the head of ears upon the head, a stem, a lug provided with a flat extremity upon the stem resting upon the back of the head intermediate the ears, and a dowel-pin traversing the lug 85 and ears.

3. In a scarf-pin, the combination with a head of ears upon the head, a stem, a lug upon the stem located intermediate the ears, a dowel-pin traversing the lug and ears, and 90 means upon the lug for retaining the parts against angular displacement.

4. In a scarf-pin, the combination with a head of ears upon the head provided with transverse perforations, a stem, a lug upon 95 the stem provided with an opening slightly larger than the perforations of the ears, and a pin traversing the hole and perforations and tightly engaging the lug and ears.

In testimony whereof I have affixed my signature in presence of two witnesses.

GEORGE W. DOVER.

Witnesses:

HORATIO E. BELLows,
WILLIAM E. BROWN.
